R. RUSSO.
CONVERTIBLE ARTICLE OF FURNITURE.
APPLICATION FILED JAN. 25, 1921.

Patented Aug. 30, 1921.

Inventor
Rocco Russo
By his Attorney
Charles L. Wright.

UNITED STATES PATENT OFFICE.

ROCCO RUSSO, OF NEW YORK, N. Y.

CONVERTIBLE ARTICLE OF FURNITURE.

1,388,895.

Specification of Letters Patent. Patented Aug. 30, 1921.

Application filed January 25, 1921. Serial No. 439,715.

To all whom it may concern:

Be it known that I, Rocco Russo, a subject of the King of Italy, residing in New York, in the county of New York and State of New York, have invented certain new and useful Improvements in Convertible Articles of Furniture, of which the following is a specification.

In a dwelling house having a small number of rooms per family, as often occurs, particularly in cities, and these rooms of limited floor area, it becomes desirable—even necessary—to select furniture of practical and useful nature in the utmost degree.

If certain of these articles can be metamorphosed in a convenient manner by easy manipulation to serve several purposes satisfactorily at different times as required, the expense of furnishing the rooms is reduced and, more important, floor space very materially conserved.

If the article is capable of being compactly folded so as to be stored in some unused available space when not required for any of its useful purposes, another advantage is manifest.

The foregoing conditions are met in the novel combination and arrangement of parts constituting a chair, crib bed or couch, according to the disposition of its elements, the same being hereinafter described in detail and shown in the accompanying drawings, forming a material part of this disclosure, and in which:

Figure 1 is a perspective view showing the article extended to form a bed or couch.

Fig. 2 is a similar view showing the same article disposed as a chair.

Fig. 3 is a side view of the same as compactly folded for storage or transportation.

Referring to the drawings in detail, the numeral 10 designates a pair of legs, substantially straight with reversely curved ends, the same being connected at the center of their length by pivots 11 with another pair of similar but reversed legs 12, both pairs of these legs having at their ends rollers 14, above which are secured cross bars 15.

The upper ends of the legs 12 are pivotally joined to the forward end of the lateral elements 16 of a rectangular frame while the corresponding ends of the legs 10 are slidably below the elements 16 of the

frame at the rear, and held when extended by a hook latch 17 pivoted on the frame.

Extending between the rear frame element 18 and the front element 19 are a plurality of slats 20, the same forming a seat-like structure.

Engaged by hinges 22 to the side frame element 16 are bars 23 constituting the lower elements of side frame and having between them and upper elements 24 a plurality of posts 25 and outer end members 26, these elements forming the sides of the seat as shown best in Fig. 2.

A pair of links 28 connect the side elements 16 with a slatted frame 30 at the front in the manner of a hinge, allowing it to be dropped, as in Fig. 2, held extended horizontally by the chains 31, as in Fig. 1, in which case it forms a prolongation of the seat, or it may be turned vertically upward and held by the hook catches 33, the same engaging knobs 34, in which position it acts as a wall when the structure is used as a crib.

At the opposite, rear end of the seat other links 36 engage a rear frame 37 which may be extended at length as shown in Fig. 1 or folded upward as in Fig. 2.

In this latter position it is held by catches 38 pivoted on the side elements 24.

Hinges 40 connect the side frames 42 which may be folded downwardly into horizontal position over the frame 37 or raised vertically and held by the catches 43 pivoted in the upper rear element 24' of the main side frame and engaging a button secured to the side frame element 24, in which position it forms an extension.

An end frame 50 is hingedly connected by links 51 at its bottom to the end of the frame 37 and may be folded downwardly into a horizontal position over the side frame elements 42 when the side elements are in closed position as shown in Fig. 2 and Fig. 3, or may be held in raised or vertical position by the catches 52 pivotally secured to the upper side element of the frame 42 thus forming a raised end or head to the bed as shown in Fig. 1, or a crib when the foot element is raised and secured in a similar manner.

Pivotally attached to the lower sides of the frame elements 37 near their outer ends are auxiliary leg members 55 braced by the cross bar element 56 to which

is removably attached a longitudinal brace bar 57 connecting with the rear cross bar 15 between the main legs 12, the bar being held by the pins 58 so as to be entirely removed when the structure is to be used as a chair as shown in Fig. 2.

The operation of compactly folding as in Fig. 3 is as follows. The side elements 24 are folded downward upon the seat elements 20 and the foot extension 30 is raised vertically and allowed to fall into horizontal position upon the folded side elements 24. The rearwardly extending side frames 42 are folded upon the back frame element 37 and the head extension frame 50 inwardly over and upon the side frames 42.

The cross bars 57 and the pins 58 being removed, the folded frame members 37-42 and 50 may be folded over and upon the seat frame members 20-24 and 30 and the auxiliary legs or support 55 folded upon frame 37. The catches 17 on being released permit the main leg members 10 and 12 to be collapsed substantially as shown in Fig. 3.

From the foregoing it will be seen that the article when extended as in Fig. 1, forms a convenient couch or single bed and when the foot element is raised the same constitutes 30 a crib for children.

Having thus described my invention and set forth the manner of its construction and use, what I claim is new and desire to secure by Letters Patent, is:—

1. An article of furniture comprising in 35 combination two pairs of crossed legs pivoted at their intersection, a platform having one set of said legs pivotally engaged thereto, the other set of legs being in slidable contact with said platform and means to prevent further movement when extended, side elements hinged at the side of said platform, elements comprising an extensible back hinged at the rear of said platform, means for holding said elements when in either a 45 horizontal or vertical position, a front element hinged to said platform and means for supporting said front element in vertical or horizontal position.

2. An article of furniture comprising in 50 combination two pairs of crossed legs pivoted at their intersection, a platform carried by said legs and capable of folding alongside thereof, extensions hinged to the front and rear of said platform, independent supports for said extensions, and railings hinged 55 at the sides of said platform and extension.

In testimony whereof I have signed my name to this application.

ROCCO RUSSO.
